ABSTRACT

A rack and pinion elevator system having at least two spaced racks and an elevator cage therebetween which carries at least one drive motor in driving engagement with each rack respectively, includes a transmission device such as a shaft which is connected to the elevator cage. At least two pinions, each engaging with a respective rack, are rigidly secured to the transmission means so that the pinions move along the racks together with the elevator cage to transfer driving forces via the transmission device from the less loaded to the more loaded side of the elevator cage thereby to substantially equalize the loads on the separate drive motors regardless of the position of the center of gravity of the load in the elevator cage.

RACK AND PINION ELEVATOR WITH AT LEAST TWO RACKS

This invention relates to an improved drive arrangement for rack and pinion elevators.

In rack and pinion elevators which, for example, climb on two racks, and which include an elevator cage which carries separate drive motors in separate driving engagement with said two racks, the motors are loaded differently in response to the position of the load in the elevator cage. When, for example, the center of gravity of the load is displaced in the elevator cage closer to one rack, then in a most unfavourable case the motor or motors acting upon that one rack must take up substantially the entire load and, therefore, be dimensioned accordingly, while the motor or motors acting upon the other rack run only with a small load.

This inconvenience is eliminated by the improved drive arrangement of the present invention. By use of a transmission device which is carried by the elevator cage and which extends between the two racks for movement along the racks with said elevator cage, the load is distributed substantially equally on the drive motors, independently of the location of the load in the elevator cage.

According to a further development of the invention, the transmission device also solves the problem of distributing the braking power from a safety means equally on the racks if the elevator cage should move at an excessive speed. The desired distribution of braking power is achieved by coupling the safety means directly to the transmission means.

The FIGURE in the attached drawing shows in a schematic way an embodiment of a device according to the invention.

1 designates an elevator cage, which is movable in the vertical direction between two poles 2 and 3 and which is guided along the same by tracks (not shown). The elevator cage is driven by separate electromotors 4 engaging in pairs via gears 5 and pinions 6 each with a rack 7 and 8 each secured on a pole. Two motors carried by the elevator cage, thus, drive the cage along the rack 7 of one pole, and two additional motors carried by the elevator cage drive the cage along the rack 8 of the other pole.

The transmission device which characterizes the present invention comprises a shaft 9 supported for rotation on the elevator cage. Its ends projecting from the cage are each rigidly fastened to a pinion 10 engaging with the respective rack 7 and 8. The shaft 9 is provided to distribute the driving force equally on the motors. When, for example, in the FIGURE the load in the elevator cage is displaced to the right, the left-hand motors operate somewhat easier and lift their side of the elevator cage somewhat before the right-hand side. As

55

a result, driving force from the left-hand motors is partially transferred to the right-hand rack 8 through shaft 9 and thereby assists the right-hand motors.

The shaft 9 is also rigidly connected to a sprocket wheel 11, which via a drive chain 12 is coupled to a sprocket wheel 13 of a safety means 14, which brakes the elevator cage via the shaft 9 when the cage exceeds a predetermined speed.

What I claim is:

1. A rack and pinion elevator system comprising a pair of horizontally spaced, vertically extending racks having an elevator cage vertically movable therebetween, drive means for selectively effecting movement of said cage along said racks comprising at least two separate drive motors carried by said cage, a first one of said drive motors having a first output shaft carrying a first output pinion which is in driving engagement with one only of said racks, a second one of said drive motors having a second output shaft separate from said first output shaft and carrying a second output pinion which is in driving engagement with the other one only of said racks, and a transmission device carried by said cage and extending between said racks for movement along said racks with said elevator cage, said transmission device being separated from said drive means and being responsive to off-center placement of a load in said cage for transferring forces from the less-loaded one of said racks to the more-loaded one of said racks thereby to substantially equalize the loads on said two drive motors, said transmission device comprising an elongated third shaft spaced from each of said first and second shafts and extending between said pair of racks in parallel relation to said first and second shafts, said third shaft being mounted for rotation at a predetermined position on said elevator cage spaced from the location of said drive motors, the opposing ends of said third shaft respectively carrying third and fourth pinions which engage said pair of racks respectively at positions spaced from each of said first and second output pinions.
2. The system of claim 1 including selectively operable braking means in engagement with said transmission device for selectively applying braking forces to each of said pair of racks via said transmission device, thereby to distribute said braking forces substantially equally to said pair of racks.
3. The system of claim 2 wherein said braking means is operably responsive to the speed of movement of said elevator cage along said racks.
4. The system of claim 1 including a sprocket wheel rigidly secured to said third shaft at a position between said third and fourth pinions, and a braking device connected via a drive chain to said sprocket wheel for selectively braking said elevator cage.
